United States Patent Office

Des. 212,638

Patented Nov. 5, 1968

212,638

CLOCK OR SIMILAR ARTICLE

Edward D. Glatz, 2025 Maple Road,
Williamsville, N.Y. 14221

Filed Nov. 27, 1967, Ser. No. 9,559

Term of patent 14 years

(Cl. D42—7)

FIG. 1 is a front perspective view of a clock or similar article embodying my new design.

FIG. 2 is a reduced scale front elevational view;

FIG. 3 is a rear elevational view thereof;

FIG. 4 is a further reduced scale top plan view;

FIG. 5 is a bottom plan view thereof;

FIG. 6 is a left side elevational view on the same scale as FIGS. 2 and 3; and

FIG. 7 is a right side elevational view thereof.

The characteristic features of my design are shown in full lines.

I claim:

The ornamental design for a clock or similar article, substantially as shown and described.
